T. L. LOFTUS

EXCAVATING MACHINE

Filed Jan. 25, 1926

Patented Mar. 8, 1927.

1,619,875

UNITED STATES PATENT OFFICE.

THOMAS LAWRENCE LOFTUS, OF DENVER, COLORADO, ASSIGNOR TO ELLEN VIRGINIA TIMM, OF DENVER, COLORADO.

EXCAVATING MACHINE.

Application filed January 25, 1926. Serial No. 33,695.

My invention relates to improvements in excavating machines, and it consists in the combinations, constructions, and arrangements herein described and claimed.

5 An object of my invention is to provide an excavating machine which is adapted to dig trenches of various widths and depths, or which may be used for digging and elevating potatoes or the like, the device when 10 used for this latter work employing a chain belt to permit the dirt to fall from the potatoes.

A further object of my invention is to provide a device of the type described which 15 is extremely simple in construction, durable and efficient for the purpose intended.

Other objects and advantages will appear in the following specification, and the novel features of the invention will be particularly 20 pointed out in the appended claim.

My invention is illustrated in the accompanying drawings, forming part of this application, in which—

Figure 1 is a side elevation of the device, 25 Figure 2 is a top plan view of the device,

Figure 3 is a plan view of a chain belt employed with the device,

Figure 4 is a plan view of the digging point,

30 Figure 5 is an enlarged fragmentary view of the device, and

Figure 6 is a section along the line 6—6 of Figure 5.

In carrying out my invention, I provide 35 a frame 1 mounted upon wheels 2. The front wheels 2 are connected to the frame 1 by means of a rocker bolster 3. A tongue 4 is connected to the bolster 3 for permitting the device to be drawn by horses. It is obvious that the device may be drawn by a 40 tractor, if desired.

The frame 1 carries uprights 5, these uprights being braced by bracing bars 6. A conveyor frame 7 is pivotally secured to the 45 uprights 5 adjacent to the top of the uprights. The conveyor frame 7 carries an endless belt 8 for conveying dirt to a chute 9. When potatoes are being dug, the belt 8 is removed and a chain belt 10 of the type 50 shown in Figure 3 is substituted therefor. This belt permits the dirt to fall from the potatoes or other articles dug while conveying the potatoes to the chute 9.

In Figure 1, I show an engine 11 which is 55 operatively connected to the conveyor belt 8

by means of a belt or chain 12. A clutch, not shown, may be used for operatively connecting or for disconnecting the engine 11 from the conveyor belt 8.

The forward end of the conveyor frame 60 7 is pivotally connected to a digging point 13 at 14. The point in turn is pivotally connected at 15 to a supporting bar 16, the latter being pivotally secured at 17 to the frame 1. The pivot pin 17 carries a sleeve 18 65 through which the bar 16 is slidably disposed. This bar is provided with a plurality of openings 19 for receiving what I term a ratchet 20, which in reality is a pin, removably disposed in any one of the openings 19.

The pin 20 is carried by a guide member 21 and this member in turn is carried by the sleeve 18 so as to be moved when the sleeve is moved. It is obvious that when the bar 16 is 70 lowered, the frame 7 will pivot about the upright 5 and will carry the digging point 13 in a circular path, thereby causing the bar 16 to pivot at the point 17.

To permit this movement, I mount an 80 idler pulley 22 on an arm 23 and pivotally secure this arm to the upright 5 at 24. A spring 25 yieldingly holds the pulley 22 in contact with the belt 12. When the frame 7 is in the position shown in Figure 1, the idler 85 pulley 22 takes up some of the slack in the belt 12. This slack is for the purpose of permitting the frame 7 to pivot about the upper ends of the uprights 5 without causing the belt to bind upon the pulley 26.

The special construction of the digging point 13 is shown in Figure 4. It will be noted from this figure that the digging point is channel-shaped and carries cutting discs 27 on the sides thereof. These discs determine the width of the trench dug. The forward end of the digging point is rounded at 28 for the purpose of scooping the dirt. Cutter points 29 are removably carried by the member 13 and are for the purpose of loosening up the ground just in front of the digging point. As the machine is moved forward, the loosened ground is received by the digging point and is then conveyed onto the conveyor belt 8 by means of an upwardly 100 curved rear end portion 30, this portion overlying the lower end of the conveyor belt.

From the foregoing description of the various parts of the device, the operation thereof may be readily understood. As 110

stated in the first part of the specification, the device may be used for digging a trench or removing potatoes or the like from the ground. When potatoes are being dug, the 5 digging point 13 is disposed substantially in the position shown in Figure 1. The chain belt shown in Figure 3 is used, and it will therefore be apparent that as the device is moved over the ground, it will remove the 10 potatoes from the ground, convey the potatoes and dirt upon the chain belt 10, and then will convey the potatoes to the chute 9, the dirt in the meanwhile dropping through the chain belt 10.

15 In digging a trench, disc cutters 27 are adjusted for the desired width of trench. In addition, the frame 7, together with the digging point 13, is lowered to the desired depth, the pin or bolt 20 being inserted in 20 one of the openings 19 as soon as the adjustment has been made. As heretofore stated, the bar 16 will slide through the sleeve 18 and will cause the sleeve to pivot on the point 17. The guide member 21 will also 25 swing with the sleeve 18, thereby keeping the bolt 20 in close proximity to the bar 16 at all times. The device is now ready for digging.

The excavator may be drawn by horses or

by a tractor, and as it is drawn forward, it 30 will dig a trench of the desired depth and width and will convey the dirt onto the conveyor belt 8, this belt subsequently delivering the dirt to the chute 9. The chute is at a sufficient height above the ground to permit 35 the chute to deliver the dirt by gravity to a wagon, if desired. The pivot point 15 is provided with clamping means, such as wing nuts 31 for rigidly securing the digging point to the bar 16. This construction 40 prevents the buckling of the digging point 13 at the points of pivot 14 and 15.

I claim:

An excavator comprising a frame, wheels for supporting said frame, a digging point, 45 cutter discs adjustably carried by said digging point, cutters carried by said digging point, means for adjusting said digging point with respect to said frame, a conveyor hingedly secured at one end to said digging 50 point and pivotally carried by said frame, an endless belt carried by said conveyor, means for actuating said endless belt, a chute disposed beneath the free end of said conveyor a sufficient distance above said frame 55 to permit the substance carried by the conveyor to be emptied into the chute.

THOMAS LAWRENCE LOFTUS.
